UNITED STATES PATENT OFFICE.

JOHN JELENC, OF PORT WASHINGTON, WISCONSIN, ASSIGNOR OF ONE-HALF TO
MARTIN JELENC, OF MILWAUKEE, WISCONSIN.

COLLAPSIBLE WARDROBE AND DRESSER.

1,372,229.

Specification of Letters Patent. Patented Mar. 22, 1921.

Application filed May 1, 1919. Serial No. 293,931.

To all whom it may concern:

Be it known that I, JOHN JELENC, a citizen of Austria, and resident of Port Washington, in the county of Ozaukee and State 5 of Wisconsin, have invented certain new and useful Improvements in Collapsible Wardrobes and Dressers; and I do hereby declare that the following is a full, clear, and exact description thereof.

10 My present invention pertains to new and useful improvements in combined wardrobes and dressers, particularly those of the collapsible type which can be reduced to a relatively small size for transportation or 15 storage.

The principal object of this invention is to improve and simplify the structure illustrated in my U. S. Patent No. 1,276,072 granted August 20, 1918.

20 Specifically the improvements consist of the addition of a chest of drawers in the nature of a dresser, and in one form the arrangement of the wardrobe or cabinet doors to completely close the front of said 25 dresser and prevent access thereto; means for strengthening the rear closure structure of the wardrobe or cabinet and to increase the rigidity of the structure when set-up position is also contemplated.

30 With these and other objects and advantages in view, the invention resides in certain novel features of construction, combination and arrangement of parts which will be hereinafter more particularly described and claimed and shown in the drawing in which:

Figure 1 represents the front elevational view of my improved combined collapsible wardrobe and dresser in set-up position.

40 Fig. 2 is a horizontal section taken substantially on the plane of the line 2—2 of Fig. 1.

Fig. 3 is a view somewhat similar to Fig. 1, but illustrating the parts in collapsed position.

45 Fig. 4 is a horizontal section on the plane of the line 4—4 of Fig. 3.

Fig. 5 is a detail rear elevational view of one lower corner of the invention, and

50 Fig. 6 is a front elevational view in set-up position of a modification of my invention.

The embodiment illustrated on Sheet 1 consists of a dresser section A and a wardrobe or cabinet section B the latter portion

of this article of furniture being so constructed and connected with the other part that it may be readily collapsed to occupy much less space than when in normal set-up position. The dresser section in the 60 present form of the invention merely consists of a vertically arranged series of drawers 1 slideable between inner and outer side walls 2 and 3 respectively and top and bottom closure members 4. The rear of 65 the dresser section is closed by a back 5 while the front is open and the outer sides of the drawers 1 are spaced inwardly slightly from the adjacent front edges of the side walls 2 and 3 as shown in Figs. 2 70 and 4.

The inner wall 2 of the dresser section forms one wall of the wardrobe section, the other side wall 6 thereof being arranged to be moved toward and away from the 75 same. The top and bottom of the wardrobe section is each constructed of a collapsible closure 7 which is broken in its center to fold inwardly as indicated in Fig. 3. The outer edges of the closures are pivoted to 80 hinge strips 8 secured to the walls 2 and 6.

Each of the closures 7 is retained in extended or set-up position by means of a swinging bar 9 movable beneath retaining fingers 10. It will be noted that the swing- 85 bars extend across the center breaks in the closure thus holding the two parts thereof in rigid alinement.

The rear of the cabinet or wardrobe section is closed by a pair of door members 12, 90 one being pivoted to the rear edge portion of each of the walls 2 and 6 and are adapted to swing inwardly into close engagement with the latter when the article is collapsed. They are retained against excessive outward 95 movement by shouldered retaining strips 11, one of which is carried by each portion of the collapsible top and bottom closures 7 and extend from the inner edges of such portions to a point adjacent the pivoted 100 connection between the latter and the hinge strips 8. In other words there is a space between the outer end of each of the retaining strips 11 and the adjacent side wall a distance equal to the width of the hinge strips 105 8. These spaces are closed by portions 12' of the rear doors 12, the adjacent top and bottom edges of the latter being shouldered as at 13 to engage the shouldered retaining strips. The inner adjacent edges of these 110

- rear doors are also shouldered to form an overlapping connection as at 14 whereby an extremely tight and rigid structure is formed.
- 5 The front of the combined dresser and wardrobe is closed by means of a pair of swinging front doors 15, one of which is hinged to the front edge of the wall 3 and the other is similarly connected to the corresponding edge of the wall 6. These doors may be swung inwardly to completely close the entrance to the dresser section and also to the wardrobe part or to lie against the walls 3 and 6 as best seen in Fig. 3. When 10 the structure is in set-up position and the doors 15 are closed as in Figs. 1 and 2 it will be obvious that access to the drawers 1 is impossible.

From the foregoing description taken in connection with the accompanying drawing, it will be obvious to anyone that in order to collapse the structure from the set-up position as indicated in Figs. 1 and 2, it is simply necessary to unlock the rear and front doors 12 and 15, swinging the former inwardly and the latter outwardly, release the swinging bars 9 from beneath their retaining fingers 10, and then press the top and bottom closures inwardly so as to draw 25 the wall 6 toward the coöoperating wall 2. This arranges the several parts of the article as depicted in Figs. 3 and 4. It will be obvious, however, that the door 15 which is hinged to the wall 3 may either be swung 30 outwardly and engaged with the outer surface of said wall or allowed to remain in its ordinary closed position to cover the entrance to the dresser section A. In setting up the article of furniture the movement of the several parts are reversed as is evident.

In the form of the invention illustrated in Fig. 6 the collapsing and setting up of the combined wardrobe and dresser is substantially identical with the similar operations of the above described form. In this modification the dresser section is designated by the character A' and the wardrobe section by B', the latter having its front 45 closed by a door 15'. This door is hinged to the outer wall 6' of the wardrobe section and extends only to the inner wall 2' thereof. In other words the front of the dresser section A' is not covered by one

portion of the wardrobe door as in the embodiment depicted in Figs. 1 to 5.

Across the top and bottom of this combined article of furniture I dispose finishing or trim strip portions 25 and 26 for an obvious purpose. Each of the portions is split into two parts as at 27 so that the part thereof over the wardrobe section may be carried by the door 15'. In some instances the parts of this trim over the wardrobe section may be made as integral with the door as shown in the illustration.

It is believed that it will be evident to the average person as well as those skilled in the art, that a very simply constructed and improved structure has been devised 70 and one which can be relatively inexpensively manufactured and marketed. Various other changes may be made in the form and proportion and in the arrangement of the several parts of the invention without departing from or sacrificing any of the principles thereof.

What is claimed is:

A collapsible article of furniture comprising a casing for a vertically arranged series 80 of drawers, one side of said casing forming one side wall of a cabinet, a second side wall for said cabinet, top and bottom closure members connected with the tops and bottoms of said side wall and foldable inwardly 85 therebetween, a pair of rear doors for the cabinet each hinged to a rear portion of one of the said side walls and foldable inwardly, said doors being of lesser width than the width of said side walls and a pair of front 90 doors for the cabinet, one of said front doors being hinged to the forward edge of the outer side wall of the cabinet, the other door being hinged to the forward edge of the outer side of the drawer casing and 95 adapted to extend across the front of the drawer casing and across a minor portion of the front of the cabinet, said front doors meeting on the center line of the combined structure and being foldable against 100 the outer sides of the casing and cabinet respectively.

In testimony that I claim the foregoing I have hereunto set my hand at Milwaukee, in the county of Milwaukee and State of 105 Wisconsin,

JOHN JELENC.
